SPINNING CUPRAMMONIUM SILK BY THE STRETCH PROCESS

Application filed September 3, 1930, Serial No. 479,512, and in Germany August 29, 1929.

In the processes heretofore known for spinning cuprammonium silk by the stretch-spinning process, the liquid jet coming out of the spinning apparatus surrounded the thread over a certain length of the same. In order to be able to subject the thread to an acid treatment the thread had to be separated from the liquid. Hitherto this was effected by leading the thread around a rod. This gives rise to a series of disadvantages. In the first place it was not possible to lead the thread into a hardening liquid directly after leaving the spinning apparatus; on the contrary, a further member must be inserted in between, since otherwise the hardening liquid mixes with the precipitating liquid carried along with the thread and its action is impaired.

A further disadvantage consists in the fact that the jet readily causes fracture of each individual filament if the thread is deviated from its vertical direction, and consequently from the freely falling stream of liquid, by means of the above mentioned rod. Since the quantity flowing through is not inconsiderable, and, moreover, the exit-opening is somewhat narrow, so that in the case of diminished pressure in the spinning apparatus no air bubbles can penetrate into the spinning apparatus, the jet or stream of liquid has a comparatively high velocity, which still further facilitates the above mentioned fracturing of the individual filaments. Owing to the fact that the friction on the rod varies in consequence of the readily changing quantity and velocity of the liquid flowing out, a braking effect of varying strength is produced and consequently a disadvantageous withdrawal of the thread from the spinning apparatus at varying rapidity.

These disadvantages are surmounted according to the present invention by drawing the thread downwards from the spinning apparatus in a vertical direction without any liquid jet surrounding the same. This is effected by drawing off the liquid or deviating it from the path of the thread before or during the exit of the thread from the spinning apparatus, but before the collecting or guiding member arranged behind the spinning

apparatus. In this manner the thread directly arrives on or in the further devices of the spinning apparatus only with the liquid adherent to its surface.

For carrying out the process according to the invention various devices may be used. The spinning apparatus constructed in the usual manner is provided at one side, preferably just above the orifice, with a siphon-like tube. This siphon tube extends with its orifice over the orifice of the exit pipe of the spinning apparatus and is provided with a tap. By suitable dimensions of the siphon tube and of the exit pipe the whole of the liquid may be made to flow away through the siphon tube and the thread issues freely from the exit pipe. If the tap in the siphon tube is closed, the apparatus operates like every known spinning apparatus, the liquid stream issuing vertically downwards with the thread. On carefully opening the tap the siphon tube fills up and a stream of the spent precipitating liquid flows away therethrough. If the orifice of the exit pipe is narrow enough practically all the spent precipitating liquid can be led away through the siphon in any direction and the moist thread alone leaves the orifice in a vertical direction. The orifice pipe of the spinning apparatus may also be surrounded by a further collecting tube somewhat wider and narrowed off at the mouth and is attached to the orifice pipe by means of a plug. The siphon tube is then branched off from the surrounding tube. This had the advantage of being more readily exchangeable.

Since in the course of the spinning process copper and cellulose precipitates deposit in the siphon tube, the quantity of liquid flowing through the latter tube continuously becomes smaller and consequently more and more liquid leaves the spinning apparatus with the thread.

In order to avoid this the liquid flowing through the siphon tube can be regulated by means of a tap. A finer regulation may be obtained by means of a vessel, adjustable as regards height, into which the siphon tube dips. By raising and lowering this vessel the suction height may likewise be adjusted.

as desired. The device has the advantage that all valves and consequently all restrictions in the siphon tube are avoided, so that the danger of the formation of deposits in the 5 siphon tube is diminished. Consequently, the quantity of the precipitating liquid flowing away through the siphon tube practically always remains the same; as a result it is ensured that the thread always leaves the spinning 10 apparatus free from precipitating liquid or with an accurately adjusted small quantity of the same. In order to exclude the undesirable influence of deposits in the siphon tube the cross section of this tube is 15 chosen as large as possible. A further advantage of the invention consists in the fact that a very fine stepwise regulation of the quantity flowing out of the outlet is possible by adjustment of the overflow vessel. 20 The process may also be carried out in practice by means of a special construction of the orifice of an ordinary spinning apparatus. It has been found that the jet of liquid coming 25 out of the spinning apparatus may be deviated from the vertical direction taken up by the thread into an inclined direction. The orifice of the exit pipe is provided on one side with a small rod or a sheet metal strip attached at an inclination to the vertical. The 30 adhesion of the precipitating liquid to the attached rod or metal strip is, in general, greater than the adhesion to the thread so that the desired separation is obtained.

Further only a part of the precipitating 35 liquid can be led off through the siphon tube or the two said devices may be combined, both the siphon tube as well as the deviating metal sheet being arranged on the spinning apparatus. In the latter case it is possible to lead 40 off only a portion of the precipitating liquor before the exit orifice, and to deviate the rest while issuing from the exit pipe.

The process offers a series of advantages in 45 spinning and permits of a simplified construction of spinning devices. Thus, the hardening liquid may be allowed to act on the thread directly after the issuance of the latter from the spinning apparatus without there being any danger of the precipitating liquor mixing 50 with the hardening liquid. It is only necessary to arrange one or several rods in an acid bath directly underneath the exit orifice of the spinning apparatus and to guide the thread, which is only superficially covered 55 with precipitating liquid, directly round these rods. If one or more rollers are arranged behind this preliminary acidifying device, over which the thread is guided and treated by spraying with a further hardening 60 liquid, then in this manner a stepwise acidification, first weak and then stronger, may be effected.

A further advantage consists in the fact that a driven roller may be arranged directly 65 below the orifice of the spinning apparatus

on to which the issuing threads may be directly guided and acidified by another hardening liquid, so that the winding rods hitherto usual, which frequently led to fracturing of the individual threads, are dispensed with. 70 From this roller, upon which an acidification of the thread may be effected, the thread is led directly, or over a second roller, to a centrifuge, to a reel, or to a bobbin.

This arrangement has the advantage that 75 it is possible to withdraw the thread from the apparatus with perfectly definite and constant velocity, since no slipping takes place, but on the contrary the thread adheres to the roller and is carried forward only by rotation 80 of same.

Moreover, by using one of the two devices 85 stretch-spinning in the vertical direction is rendered possible. For this the spinning apparatus, the guiding and withdrawal rollers, and the receiving apparatus for the thread are arranged underneath one another in a vertical direction. In this way satisfactory 90 supervision is attained, as well as narrow machine construction and consequently considerable saving of space. In this arrangement the rollers are embraced by the thread through an angle of 360°. On account of this comparatively large angle this arrangement 95 is particularly adapted for the stretch-spinning process since slipping of the thread on the rollers is avoided with certainty.

The acidification may be carried out in 100 various ways. Troughs may be arranged underneath the stretching or guiding rollers into which the said rollers dip so that the hardening liquid attached to them is carried along by adhesion and covers the rollers in the form of a thin layer. By this means the 105 thread is brought into contact with the hardening liquid in the course of its motion over the roller. Further one or both rollers may be sprayed with acid from above or below and the liquid dropping off the roller may be 110 caught in a collecting trough.

Finally it is possible to carry out a stretch spinning with displaced rollers. The one, driven, roller is arranged directly under the spinning apparatus, whilst another roller is 115 above and displaced with respect to the first. The threads issuing vertically downwards from the spinning apparatus is guided over half the circumference of the roller arranged directly under the orifice of the spinning apparatus, is guided vertically upwards after leaving this roller, is passed over the upper half of the circumference of the roller displaced with respect to the first roller and is led to a centrifuge, to a reel or to a bobbin. 120 125

In this way, firstly a comparatively low structural height for the machine is obtained and secondly both rollers are uniformly embraced by the thread over half the circumference. The two last named constructional 130

forms permit the thread to embrace both rollers with the same angle.

The drawings show schematically by way of example devices for carrying out the process according to the present invention in the above forms.

Fig. 1 shows a spinning apparatus with a laterally disposed siphon tube and the thread led directly into the acid trough;

Fig. 2 shows a spinning device having a withdrawal roller arranged underneath the exit orifice embraced over three quarters of its circumference with the thread and sprayed with hardening liquid;

Fig. 3 shows a spinning device with a strip which produces deviation of the course of the liquid at the exit orifice of the spinning vessel;

Figs. 4 and 5 show spinning devices with vertical and displaced arrangement of the withdrawal rollers;

Fig. 6 shows the regulating device for the quantity of flow in the siphon tube.

The spinning apparatus shown in Fig. 1 consists of one of the known cylindrical spinning apparatus 1 provided with an inlet opening 18 and having positioned within it a funnel 19 with an outlet pipe 2 which is surrounded by a further surrounding tube 3. The surrounding tube 3 is connected with the exit pipe 2 by means of a seal 5. At about the level of the orifice of the exit pipe 2 an angularly-bent siphon tube 4 is attached laterally to the surrounding pipe 3. By means of a tap 6 provided in the siphon tube 4 the quantity of the liquid to be drawn off may be adjusted. The thread now issuing from the spinning pot with only superficially adhering liquid is guided directly over two rods 13 situated in a hardening bath 12 underneath the spinning apparatus 1 and thereby subjected to acidification.

Fig. 2 shows the same spinning device as Fig. 1 provided with the surrounding pipe 3 and the siphon tube 4, but the thread issuing from the spinning apparatus is successively guided in a horizontal direction over two rollers 7 and 8 and after leaving the second roller is led to a centrifuge 9. On the first roller 7 the thread is treated by spraying with acid from a small tube 14.

In Fig. 3 the siphon tube is dispensed with on the spinning apparatus. In its place a diverging sheet metal member 10 is arranged which embraces the surrounding pipe 3 just before the orifice in a socket-like manner and diverts the liquid stream from its course.

In Fig. 4, the spinning device shown in Fig. 1, the two withdrawal rollers 7 and 8 and the centrifuge 9 are arranged vertically over one another.

In Fig. 5 the spinning apparatus 1, the two withdrawal rollers 7 and 8 and the centrifuge 9 are arranged in such a manner that the thread issuing vertically from the spinning

apparatus is passed around the first roller 7 so as to make contact over an angle of 180°, is then led vertically upwards, is passed around the second roller 8 which is displaced from and above the first roller so as likewise to make contact over 180°, and is finally led vertically downwards to the centrifuge 9.

In Fig. 6 the spinning apparatus is surrounded at its lower portion 2 with the pipe 3 which narrows in the downward direction and is connected with the portion 2 by means of an elastic seal 5. Just below the seal a siphon tube 4 branches off which projects downwardly beyond the orifice of the pipe 3 and here carries a funnel-shaped overflow vessel 16, which is held in place by means of a resilient sleeve 7 embracing the siphon tube 4.

The manner in which the regulating device acts may be explained as follows. During the spinning the threads together with the precipitating liquid pass out through the spinning apparatus 2 and through the pipe 3. Since the opening of the pipe 3 is smaller than that of the exit pipe 2 the pipe 3 soon fills with liquid until the latter overflows into the siphon tube 4, fills the vessel 16, and then streams over the edge of the same. The portion of the precipitating liquid flowing away through the siphon tube 4 may be regulated by adjusting the vessel 16 in the arrow direction α whereby the distance between the orifice of the pipe 3, from which the thread issues, and the surface of the liquid flowing away over the edge of the vessel 16, which determines the suction head, is adjusted.

What we claim is:

1. A process for producing cellulosic filaments, comprising extruding a cellulosic solution to form filaments, stretching the extruded filaments by the motion of a stream of precipitating liquid, and diverting the precipitating liquid from the filaments while continuing the movement of the filaments in the same direction.

2. A process for producing cellulosic filaments, comprising extruding a cellulosic solution into a downwardly moving stream of precipitating liquid and diverting the precipitating liquid from the filaments while continuing the movement of the filaments in the same direction.

3. A process as defined in claim 2, in which the precipitating solution is diverted by retarding its movement with the filaments and siphoning off the precipitating liquid at a point above the point of retardation.

4. A process as described in claim 2, in which the liquid is diverted from the filaments by contacting it with a material having a greater adhesion for the liquid than do the filaments.

5. A process for producing cellulosic fila-

- ments, comprising extruding a cellulosic solution into a downwardly moving stream of precipitating liquid, diverting precipitating liquid from the filaments by retarding the movement of the precipitating liquid with the filaments and siphoning off precipitating liquid above the point of retardation, the proportion of liquid continuing with the filaments being controlled by regulating the quantity of liquid siphoned off.
6. In the preparation of cellulosic filaments, the steps comprising extruding a cellulosic solution into a downwardly moving stream of precipitating liquid and diverting the precipitating liquid from the filaments while moving the latter in the same direction into a hardening liquid.
7. A process for the stretch spinning of filaments, comprising the steps of extruding a cellulosic solution into a spinning apparatus having a restricted orifice through which the filaments pass, leading a constant flow of precipitating liquid into the apparatus and leading away the used precipitating liquid at a point above the said orifice.
8. An apparatus of the class described, comprising a spinning nozzle, a spinning vessel positioned below the spinning nozzle and adapted to receive filaments extruded through the spinning nozzle, means for moving a stream of precipitating liquid downwardly through the spinning vessel in contact with the filaments, and means for diverting the precipitating liquid from the filaments while continuing the movement of the latter in the same direction.
9. An apparatus of the class described, comprising a spinning nozzle, a downwardly extending tube positioned below said spinning nozzle and adapted to receive the filaments extruded therefrom, means for passing a stream of precipitating liquid through said tube and means for diverting the precipitating liquid from the filaments while moving in a downwardly direction.
10. An apparatus of the class described, comprising a spinning vessel, a spinning nozzle, a spinning nozzle arranged at the upper end of said vessel, an inlet connected with said vessel, an outlet tube arranged at the lower end of said vessel, a tube for leading away used precipitant located above the orifice of said outlet tube and having means associated therewith for regulating the flow of the used precipitant.
11. An apparatus of the class described, comprising a spinning vessel, a spinning nozzle arranged at the upper end of said vessel, an inlet connected with said vessel, an outlet tube arranged at the lower end of said vessel, a tube for leading away used precipitant located above the orifice of said outlet tube and means in said tube for regulating the flow of the used precipitant.
12. In a device of the class described, a spinning vessel, a spinning nozzle arranged at the upper end of said vessel, an inlet for the precipitant, a narrow outlet tube arranged at the lower end of said vessel, and a siphon tube positioned above the orifice of said outlet tube, said siphon tube extending into a vessel having a liquid level above the outlet of the siphon tube.
13. In a device of the class described having a spinning vessel, a spinning nozzle arranged at the upper end of said vessel, means for supplying precipitating liquid to said vessel, a narrow outlet tube arranged at the bottom of said vessel, a siphon tube connected with the lower part of the vessel above the orifice of the outlet tube, said siphon tube extending into a vessel having a liquid level adjustable vertically relative to the outlet of the said outlet tube.
14. In an apparatus of the class described, a spinning nozzle, a downwardly extending tube adapted to receive filaments extruded from the spinning nozzle, means for supplying precipitating liquid to said tube and a piece of material, having a greater adhesion to the precipitating liquid than the filaments, positioned so as to contact with the precipitating liquid leaving the tube and to divert it from the filaments.
15. In an apparatus of the class described, a spinning nozzle, a downwardly extending stretch spinning tube positioned to receive filaments extruded from the spinning nozzle, means for supplying precipitating liquid to the upper end of the spinning tube, and a piece of metal, having greater adhesion for the precipitating liquid than do the filaments, positioned so as to contact with the liquid leaving the spinning tube and bent to divert the stream of liquid from the filaments.
16. A process for producing cellulosic filaments, comprising extruding a cellulosic solution to form filaments, stretching the extruded filaments by the motion of a stream of precipitating liquid, drawing off a portion of the precipitating liquid while retarding the movement of the liquid with the filaments and diverting the remainder of the precipitating liquid from the filaments after passing through the orifice.
17. In a device of the class described, a spinning apparatus having a restricted orifice through which the filaments pass, means for extruding a spinning solution thereto, means for supplying a flow of precipitating liquid to the said spinning apparatus, an outlet for used precipitating liquid above the said orifice and means for diverting the remainder of the precipitating liquid from the filaments after passing through the orifice and while moving in the said direction.
- In testimony whereof we affix our signatures.
- AUGUST HARTMANN.
